REMOTE INDICATION APPARATUS

Paul H. Crago, Wilkinsburg, Pa., assignor to The Union Switch & Signal Company, Swissvale, Pa., a corporation of Pennsylvania

Application January 25, 1934, Serial No. 708,271

8 Claims. (Cl. 246—124)

My invention relates to remote indication apparatus, and has for an object the provision of novel and improved means for continuously indicating at a remote point, such, for example, as a dispatcher's office, the traffic conditions existing in two sections of a railway track, the different indications being transmitted by direct current over a single line circuit.

One feature of my invention is the provision of apparatus of this character wherewith conflicting indications may be continuously transmitted over a single pair of line wires by direct current, and which apparatus is so arranged that false indications by what is known as "signal flashes" are avoided. Other features and advantages of my invention will appear as the specification progresses.

I will describe two forms of apparatus embodying my invention, and will then point out the novel features thereof in claims.

In the accompanying drawing, Fig. 1 is a diagrammatic view showing one form of indication apparatus embodying my invention. Fig. 2 is a view showing a modification of the apparatus of Fig. 1 wherein a single battery in place of a split battery is provided, and which apparatus also embodies my invention.

Similar reference characters refer to similar parts in each of the views.

Referring first to Fig. 1, the reference characters 1 and 1^a designate the track rails of a stretch of railway track which rails are divided by the usual insulated rail joints to form two track sections 1T and 2T. Each track section 1T and 2T is provided with a track circuit comprising a battery 3 and a track relay designated by the reference character R with a prefix corresponding to the section. Although the track sections 1T and 2T are here disclosed as being adjacent sections, it will be understood that I do not wish to limit myself to this one arrangement, and these sections may be otherwise disposed with respect to each other should it seem desirable.

Located adjacent the track sections 1T and 2T are two relays 1AT and 2AT preferably of the direct current neutral type. The relays 1AT and 2AT are normally deenergized and are preferably provided with rectifiers 4 and 5, respectively, which rectifiers are connected across the winding of the associated relay in a direction to snub the winding as the relay is deenergized for causing the relay to be slow releasing in character. Also located adjacent the track sections is a source of direct current here shown as a battery 6 having a positive terminal B, a negative terminal N

and a central terminal C. That is, the battery 6 is what is commonly known in the signaling art as a split battery. The function of the relays 1AT and 2AT and the battery 6 will shortly appear.

Located at a point remote from the track sections 1T and 2T, such, for example, as in a dispatcher's office, are two indicator lamps 1AK and 2AK corresponding respectively to the track sections 1T and 2T. These lamps are controlled by relays 1AKR and 2AKR, respectively, the circuit for the lamp 1AK being easily traced and including a front contact 7 of the relay 1AKR, while the lamp 2AK is provided with a similar circuit which includes a front contact 8 of the relay 2AKR. The relays 1AKR and 2AKR are preferably direct current neutral relays of the usual type and are provided with a line circuit extending from the office station to the field station and which includes a pair of line wires designated by the reference characters L and Com.

A bridge type rectifier 9 is interposed between the relays 1AKR and 2AKR and the line wires L and Com in the following manner. The line wires L and Com are connected with the terminals 10 and 11 of the rectifier 9, respectively. The winding of the relay 1AKR has one terminal connected with the terminal 12 of the rectifier 9 and its opposite terminal connected directly with the line wire Com, while the winding of the relay 2AKR has one terminal connected with the terminal 13 of the rectifier 9 and its other terminal connected with the line wire Com. Asymmetric units of the bridge rectifier 9 are arranged as illustrated in the drawing, and thus it follows that when the line wire L is positive with respect to the line wire Com, current will flow from the line wire L through the asymmetric unit in the bridge arm 10—12 of the rectifier 9 in its low resistance direction and the winding of the relay 1AKR to the line wire Com and that relay will become energized. The asymmetric unit in the arm 11—12 of the rectifier 9 will in this instance act as a snub to the winding of the relay 1AKR when that relay is deenergized with the result that the relay 1AKR is provided with a slow-release characteristic. When the line wire Com is positive with respect to the line wire L, current will flow through the winding of the relay 2AKR and the asymmetric unit in the bridge arm 10—13 in its low resistance direction and that relay will be energized. The asymmetric unit in the bridge arm 11—13 will in this instance serve as a snub to the winding of the relay 2AKR when that relay is deenergized with the result that the relay

75

80

85

90

95

100

105

110

115

2AKR is provided with a slow-release characteristic.

As shown in Fig. 1, both track sections 1T and 2T are unoccupied, both track relays 1TR and 2TR are picked up, no current is supplied to the line circuit and both indicator lamps 1AK and 2AK are dark. I shall now assume that a train enters the track section 1T from the left and the track relay 1TR is shunted, the track section 2T remaining unoccupied. With the track relay 1TR released, current will flow from the B terminal of the battery 6 over a back contact 14 of the track relay 1TR, back contact 15 of the relay 1AT, line wire L, asymmetric unit of the bridge arm 10-12 of the rectifier 9 in its low resistance direction, winding of relay 1AKR and thence by the line wire Com to the C terminal of the battery 6, and the relay 1AKR will be energized, and the indicator lamp 1AK will be illuminated to indicate at the dispatcher's office the occupancy of the track section 1T. It follows, that as long as the track section 1T is occupied and not the track section 2T, relay 1AT remains deenergized and current of positive polarity is continuously supplied to the line circuit and the indicator 1AK is continuously displayed. I shall next assume that a train enters the section 2T from the right at a time when the track section 1T is unoccupied so that the track relay 2TR is released and the track relay 1TR is picked up. With the track relay 2TR released, current will flow from the B terminal of the battery 6 over a back contact 16 of the relay 2TR, back contact 17 of the relay 2AT, winding of the relay 1AT and to the C terminal of the battery 6, and the relay 1AT will be held steadily energized. In response to the relay 1AT being picked up, current will flow from the C terminal of the battery 6 over the line wire Com, winding of the relay 2AKR, asymmetric unit of the bridge arm 10-13 of rectifier 9 in its low resistance direction, line wire L, front contact 18 of relay 1AT and to the negative terminal N of the battery 6, and relay 2AKR will be energized to cause the lamp 2AK to be illuminated to indicate at the dispatcher's office the occupancy of the track section 2T. Consequently, as long as the track section 2T is occupied and not the other section, the relay 1AT is held steadily energized and current of negative polarity is continuously supplied to the line circuit and the indicator 2AK is steadily displayed. I shall next assume that both track sections 1T and 2T are occupied at the same time so that both track relays 1TR and 2TR are shunted. Under this condition, current will flow from the B terminal of the battery 6 over the back contact 16 of the track relay 2TR, back contact 17 of relay 2AT, winding of relay 1AT and to the C battery terminal, and the relay 1AT will be energized. When the relay 1AT picks up, current will flow from the B terminal of the battery 6 over back contact 14 of the track relay 1TR, a front contact 19 of the relay 1AT, winding of the relay 2AT and the C terminal of battery 6, and that relay will be energized. As the relay 2AT picks up, the circuit to the relay 1AT is opened at the back contact 17 and relay 1AT is released at the end of its slow-release period, opening the front contact 19 in the circuit to the relay 2AT and that relay is released at the end of its slow-release period, with the result that both relays 1AT and 2AT are now deenergized ready to start the operation over again. It is clear, therefore, that with both track relays 1TR and 2TR released, the relay 1AT will be operated to alternately close the front contact 18 and the

back contact 15. Each period that the relay 1AT is picked up and the front contact 18 is closed, current of negative polarity is supplied to the line circuit to energize the relay 2AKR at the office station. At each period when the relay 1AT is released and the back contact 15 is closed, current of positive polarity is supplied to the line circuit and the relay 1AKR at the office station is energized. The parts are so proportioned and adjusted that the relays 1AKR and 2AKR will remain picked up from the one operation to the next of the relay 1AT and, consequently, both indicators 1AK and 2AK will be continuously displayed in response to the occupancy of both track sections 1T and 2T.

It is clear from the foregoing description that should the track section 1T now become vacated, leaving the track section 2T only occupied, the track relay 1TR will pick up leaving the relay 1AT steadily energized over the circuit including the back contact 16 of the relay 2TR and the back contact 17 of the relay 2AT with the result that current of negative polarity will now be continuously supplied to the line circuit and only the relay 2AKR at the office station will be energized, and only the indicator 2AK will be displayed, the indicator 1AK becoming dark upon the release of the relay 1AKR. In the event that both track sections are occupied and the section 2T is vacated previous to the vacating of the section 1T, the track relay 2TR will be picked up, leaving the relay 1AT without current and that relay will be released with the result that current of positive polarity will be steadily supplied to the line circuit and the relay 1AKR at the office station only will be energized. In this instance, the indicator 1AK remains displayed while the indicator 2AK becomes dark upon the release of the relay 2AKR.

Referring to Fig. 2, a single battery 20 is provided in place of the split battery 6 of Fig. 1 and the connection of its terminal C with the line wire Com is governed by the relay 1AT. The track relays 1TR and 2TR of Fig. 2 are governed by traffic conditions of the two track sections 1T and 2T the same as in Fig. 1 and these track relays in turn control the relays 1AT and 2AT in identically the same manner as in Fig. 1, and it is thought unnecessary to repeat the description. When the relay 1AT is deenergized, the line wire Com is connected with the C terminal of the battery 20 over a back contact 21 of the relay 1AT, and when that relay is picked up, this line wire is connected with the B terminal of the battery 20 over a front contact 22 of the relay 1AT. It is clear, therefore, that with the track relay 1TR only released, the relay 1AT remains deenergized, and current of positive polarity is continuously supplied to the line circuit. When the relay 2TR is released, the relay 1AT is picked up, and current of negative polarity is continuously supplied to the line circuit, and when both the track relays are released, the relay 1AT is operated, and currents of positive and negative polarities are alternately supplied to the line circuit. In each case the contacts 21 and 22 function in conjunction with the contacts 15 and 18 to pole change the connection of the battery 20 with the line wires L and Com. It is apparent that the apparatus of Fig. 2 will function in the same manner as the apparatus of Fig. 1 described hereinbefore, to indicate at the office station the traffic conditions of the sections 1T and 2T.

Although I have herein shown and described only two forms of apparatus embodying my in-

80

vention, it is understood that various changes and modifications may be made therein within the scope of the appended claims without departing from the spirit and scope of my invention.

5 Having thus described my invention, what I claim is:

1. In combination, two sections of railway track, a track circuit including a track relay for each section, a line circuit comprising two line wires extending from said track sections to an office station and provided with a source of direct current at the end adjacent said track sections, a first and a second relay located adjacent said track sections and both normally deenergized, circuit means for continuously energizing said first relay effective when a particular one of said track relays is shunted but not the other and including a back contact of said second relay, other circuit means for energizing said second relay effective when both of said track relays are shunted and including a front contact of said first relay; whereby said first relay is continuously energized when said particular track relay is shunted, said first relay is alternately energized and deenergized when both track relays are shunted and remain continuously deenergized when said other track relay only is shunted, means effective to supply current of one polarity to the line circuit from said source including a back contact of said other track relay and a back contact of said first relay, means effective to supply current of the opposite polarity to the line circuit from said source including a front contact of said first relay; and indicating means located at the office station connected with said line circuit selectively responsive to steady direct current of one polarity, steady direct current of opposite polarity and to direct current alternating in polarity.

40 2. In combination, two sections of railway
track, a track circuit including a track relay for
each section, a line circuit comprising two line
wires extending from said track sections to an
office station and provided with a source of
45 direct current at the end adjacent said track sec-
tions, a first and a second relay located adjacent
said track sections and both normally deener-
gized, circuit means for continuously energizing
50 said first relay effective when a particular one of
said track relays is shunted but not the other
and including a back contact of said second relay,
other circuit means for energizing said second
relay effective when both of said track relays are
55 shunted and including a front contact of said first
relay; whereby said first relay is continuously en-
ergized when said particular track relay is
shunted, said first relay is alternately energized
and deenergized when both track relays are
60 shunted and remain continuously deenergized
when said other track relay only is shunted;
means effective to supply current of one polarity
to the line circuit from said source including a
back contact of said other track relay and a back
65 contact of said first relay, means effective to sup-
ply current of the opposite polarity to the line
circuit from said source including a front con-
tact of said first relay; a first and a second loop
70 circuit connected with said line circuit at the
office station each including a winding and an
asymmetric unit, said asymmetric units arranged
75 that one passes current of one polarity and the
other passes current of the opposite polarity and
a first and a second indicator controlled by the
windings of said first and second loop circuits re-
spectively.

3. In combination, two sections of railway track, a track circuit including a track relay for each section, a line circuit comprising two line wires extending from said track sections to an office station and provided with a source of direct current at the end adjacent said track sections, a first and a second relay located adjacent said track sections, and both normally deenergized, circuit means for continuously energizing said first relay effective when a particular one of said track relays is shunted but not the other and including a back contact of said second relay, other circuit means for energizing said second relay effective when both of said track relays are shunted and including a front contact of said first relay; whereby said first relay is continuously energized when said particular track relay is shunted, said first relay is alternately energized and deenergized when both track relays are shunted and remain continuously deenergized when said other track relay only is shunted; means effective to supply current of one polarity to the line circuit from said source including a back contact of said other track relay and a back contact of said first relay, means effective to supply current of the opposite polarity to the line circuit from said source including a front contact of said first relay, a first and a second winding located at the office station and connected with said line circuit, a bridge rectifier interposed between said windings and said line wires of the line circuit; said rectifier arranged in such a manner that a first arm passes current of one polarity to the first winding, a second arm passes current of the opposite polarity to the second winding, a third arm snubs the first winding to provide the winding with a slow-release period and the fourth arm snubs the second winding to provide that winding with a slow-release period; and a first and a second indicator controlled by said windings. 115

4. In combination, two sections of railway track, a track circuit including a track relay for each section, a line circuit comprising two line wires extending from said track sections to an office station and provided with a source of direct current at the end adjacent said track sections, a relay located adjacent said track sections and normally deenergized, circuit means for continuously energizing said relay in response to a train occupying a particular one of said sections and including a back contact of the track relay of that section, other circuit means operating to alternately energize and deenergize said relay in response to both sections being occupied and including a back contact of each of said track relays, means effective to supply current of one polarity to the line circuit from said source including a back contact of the other of said track relays and a back contact of said relay, means effective to supply current of the opposite polarity to the line circuit from said source including a front contact of said relay; and indicating means located at the office station connected with said line circuit selectively responsive to steady direct current of one polarity, steady direct current of the opposite polarity and to direct current alternating in polarity. 120 125 130 135 140

5. In combination, two sections of railway track, a track circuit including a track relay for each section, a line circuit comprising two line wires extending from said track sections to an office station and provided with a source of direct current at the end adjacent said track sections, a relay located adjacent said track sections and 115 153

normally deenergized, circuit means for continuously energizing said relay in response to a train occupying a particular one of said sections and including a back contact of the track relay of 5 that section, other circuit means responsive to both track sections being occupied and including a back contact of each of said track relays and effective to operate said relay to alternately close a front and a back contact of said relay for substantially equal periods, means effective to energize the line circuit with current of one polarity from said source and including a back contact of the other of said track relays and said back contact of said relay, means effective to energize the 10 line circuit with current of the opposite polarity from said source and including said front contact of said relay; and indicating means located at the office station connected with said line circuit selectively responsive to steady direct current of one 15 polarity, steady direct current of the opposite polarity and to direct current alternating in polarity.

6. In combination, two sections of railway track, a track circuit including a track relay for 25 each section, a line circuit comprising two line wires extending from said track sections to an office station; a battery located adjacent said sections provided with a positive terminal B, a negative terminal N and a central terminal C; a relay 30 located adjacent said track sections and normally deenergized, circuit means for connecting the winding of said relay across the B and C terminals of said battery and including a back contact of a particular one of the track relays and operative 35 to steadily energize said relay in response to a train occupying the associated section, other circuit means for connecting the winding of said relay across the B and C terminals of the battery including a back contact of each of said track 40 relays and operative to alternately energize and de-energize said relay in response to both track sections being occupied, means to connect one of said line wires with the C battery terminal, means to connect the other line wire with the B battery 45 terminal including a back contact of said relay and a back contact of the other of said track relay, means to connect said other line wire with the N battery terminal including a front contact of said relay; and indicating means located at the 50 office station connected with said line wires selectively responsive to steady direct current of positive polarity, steady direct current of negative polarity and to direct current alternately positive and negative in polarity.

55. 7. In combination, two sections of railway track, a track circuit including a track relay for

each section, a first and second line wire extending from said track sections to an office station, a battery located adjacent said sections, a relay located adjacent said sections and normally de-energized, circuit means including a back contact 80 of a particular one of said track relays for connecting the winding of said relay across the battery to steadily energize said relay in response to a train occupying the section associated with that track relay, other circuit means including a back contact of each of the track relays for connecting the winding of said relay across the battery and operative to alternately energize and deenergize said relay in response to both track sections being occupied, means to connect the first line wire with the positive terminal of the battery including a first back contact of said relay and a back contact of said other track relay, means to connect the second line wire with the negative terminal of the battery including a second back contact of said relay, means to connect the first and second line wires with the negative and positive terminal of the battery respectively including a first and a second front contact of said relay respectively, and indicating means located at the office station 90 connected with the line wires selectively responsive to current of positive or negative polarity or to current alternating in polarity.

8. In combination, two sections of railway track, a track circuit including a track relay for 105 each section, a line circuit comprising two line wires extending from said track sections to an office station and provided with a source of current at the end adjacent said track sections, a first and a second winding located at the office 110 station connected with said line circuit, a bridge rectifier interposed between said windings and said line wires; said rectifier arranged in such a manner that a first arm passes current of positive polarity to the first winding, a second arm passes 115 current of negative polarity to the second winding, a third arm snubs the first winding to provide it with a slow-release period and the fourth arm snubs the second winding to provide it with a slow-release period; a first and a second indicator 120 controlled by said first and second windings respectively; means for energizing said line circuit with current of positive polarity from said source including a back contact of a particular one of said track relays, means to energize the line circuit with current of negative polarity including a back contact of the other track relay, and means to energize said line circuit alternately with currents of positive and negative polarities including a back contact of each of said track relays. 125
